(57) **CLAIM**

The ornamental design for vehicle charger adapter, as shown and described.

DESCRIPTION

FIG. 1 is a perspective view of a vehicle charger adapter showing the new design;

FIG. 2 is a front elevational view thereof;

FIG. 3 is a right-hand side elevational view thereof; (the left-hand side elevational view is a mirror image of FIG. 3);

FIG. 4 is a rear elevational view thereof;

FIG. 5 is a top plan view thereof;

FIG. 6 is a bottom plan view thereof;

FIG. 7 is a perspective view of another embodiment of a vehicle charger adapter;

FIG. 8 is a front elevational view thereof;

FIG. 9 is a right-hand side elevational view thereof; (a left-hand side elevational view is a mirror image of FIG. 9);

FIG. 10 is a rear elevational view thereof;

FIG. 11 is a top plan view thereof;

FIG. 12 is a bottom plan view thereof;

FIG. 13 is a perspective view of a further embodiment of a vehicle charger adapter;

FIG. 14 is a front elevational view thereof;

FIG. 15 is a right-hand side elevational view thereof; (a left-hand side elevational view is a mirror image of FIG. 15)

FIG. 16 is a rear elevational view thereof;

FIG. 17 is a top plan view thereof; and,

FIG. 18 is a bottom plan view thereof.
